UNITED STATES PATENT OFFICE

EARL S. GOMES, OF CINCINNATI, OHIO

SHIPPING CARTON

REISSUED

Application filed May 6, 1931. Serial No. 535,463.

My invention relates to shipping cartons and more particularly to a fibreboard carton used for shipping radios and the like.

Heretofore various types of inner supports for fibreboard shipping cases have been devised but all of said supports, to the best of my knowledge, are difficult to insert within the carton, do not readily maintain their proper placement and, in the majority of instances, it is necessary to place the article to be shipped within the carton and then insert the inner supports in order to keep them together and at the proper supporting position relative to the article to be shipped.

The object of my invention, generally stated, is to provide improved inner supports for cartons of the class above specified which are simple, efficient, economical to manufacture, easily inserted within and removed from the carton and will maintain their proper placement within the carton both before and after the radio or like article to be shipped is packed therein.

Another object of my invention is to provide inner supports for fibreboard shipping cartons which can be easily assembled by the carton manufacturers ready for use, thus eliminating the usual time required of the packer in assembling said supports.

More specifically stated, my object is to provide a carton which may be quickly set up without the use of glue, paste or staples and which will hold a radio cabinet suspended off of its legs and in such a manner that all parts of the cabinet will be so suspended that no part thereof will come into contact with the carton or outer container.

Another object of the invention is to provide simple and efficient protective means to firmly hold the cabinet in fixed, non-sliding relation to the top plate, thereby preventing the surface of the cabinet from being marred by rubbing.

A still further object of my invention is to provide an improved fibreboard top plate which is of a size suitable for snugly fitting within the top of the carton.

My invention consists in the construction, combination, location and arrangement of parts, all as herein set forth and claimed.

In the drawings:

Fig. 1 is a perspective phantom view of a fibreboard shipping carton showing, by full lines, my improved inner supports and the relative position they assume within the bottom portion of the carton; 55

Fig. 2 is a perspective view of the main or body part of one of the supports;

Fig. 3 is a perspective detail of one of the flat panels; 60

Fig. 4 is a perspective detail of one of the wedge supporting and strengthening strips;

Fig. 5 is a perspective view of the wooden brace usually employed in shipping radios; 65

Fig. 6 is a top view of one of the supports shown in Fig. 1;

Fig. 7 is a vertical section through a fibreboard shipping carton showing my improved inner supports and top plate for spacing an article to be shipped from the side walls and 70 top and bottom of the carton;

Fig. 8 is a perspective view, partly in section, of the top plate, one of the side pads being partly shown in section to clearly illustrate its assemblage with the plate; 75

Fig. 9 is a cross section of the top plate and side pads taken on a plane corresponding to line 9—9 of Fig. 11;

Fig. 10 is a plan view of the blank of the top plate before bending; and 80

Fig. 11 is a bottom view of the top plate and side pads and showing the outline of the radio by broken lines.

The structure hereinafter described is particularly adapted to be used as a shipping 85 container for console type radio cabinets with radio receiver and speaker installed, or any other like cabinet or piece of furniture.

In the embodiment of my invention as illustrated and which shows a preferred construction I provide a shipping carton 1, which is preferably but not necessarily composed of double-wall fibreboard and is provided with side flaps 2—2 and end flaps 3—3 at the top and bottom to close the top and bottom of 95 said carton in a manner well known.

Referring now in detail to one of the inner supports for the carton 1, I have shown a radio cabinet as the article to be shipped which is designated 4 and shown by dotted 100

outline in Fig. 7, but it is to be understood that various other articles, such as furniture, can be shipped, the inner supports not being limited to supporting radio cabinets but 5 being adapted to support any article of a similar nature.

As shown in detail in Fig. 2, 5 designates the body of one of the inner supports which is preferably formed from a blank of corrugated fibreboard scored and died out so 10 that when said blank is folded it will appear as shown in Fig. 2. This body 5, being scored on the lines 6, 7, 8, 9, 10 and 11, respectively, and died out at 12 and 13, when bent, forms 15 aligned end walls 14—14 and relatively short oppositely disposed side walls or flanges 15—15. The end walls 14—14 are integrally joined together by the U-shaped inset portion 16, which portion is provided with down- 20 wardly depending support 18. 19 represents one of the flat panels, a detail of which is shown in Fig. 3, and numerals 20—20 designate slots in said panel which are of a width suitable for receiving the side walls 17 of the 25 U-shaped inset portion 16, as will presently be described. Wedge strengthening strip 21, shown in Fig. 4, is of a width suitable for being received between the side walls 17 of the U-shaped inset portion 16, as shown in Fig. 6. After the body 5 has been scored and died out, as described, and bent on the scored lines to the position shown in Fig. 2, two of the flat panels 19 are placed between the 30 downwardly depending support 18 and the end walls 14—14 and pushed inwardly so that the slots 20—20 of said panels receive the side walls 17—17 of the inset portion 16, the depth of the slots being equal to the depth of the side walls 17. The panels are then 35 pushed upon the side walls 17 and the top edges 20a are brought into alignment or flush with the top edges 17a of the side walls 17, as shown in Fig. 1. One of the wedge strengthening strips 21 is then inserted be- 40 tween panels 19 and between the walls 17—17 of the inset portion 16, as shown in Fig. 6, thus wedging panels 19 tightly against the body 5 or sufficiently so to hold them rigid relative to one another. Two of the inner 45 supports are then placed within the carton 1, as shown in Fig. 1, and the carton is ready to receive the article to be shipped.

In the present showing I have illustrated a radio cabinet 4 as the article to be shipped 50 and in this showing it is customary to provide a wooden support such as shown in Fig. 5. This wooden support comprises cross member 22 and end members 23 and 24, which end members are preferably nailed to the cross 55 member 22 as shown. The cross member 22 is then secured to the bottom of the radio cabinet 4 in any suitable manner as, for example, by nails 25, as shown in Fig. 7 and with the wooden support thus attached to the cabinet 60 4, said cabinet can be placed within the carton

1, the end members 23 and 24 being supported upon the top edges 20a of the flat panels 19 and the top edge 17a of the side walls 17 and upon the top edge 21a of the wedge strengthening strip 21, as shown in Fig. 7. The entire weight of the cabinet 4 is thereby carried by the inner supports as the legs 26 are spaced from the bottom of the carton 1, thereby preventing the legs from being broken and also preventing holes being punched in the carton by the legs.

Referring now to the top plate of the carton and to Fig. 10, 27 designates a blank which is notched or cut away at 28 and scored, as shown by the dotted lines. The ends of the blank 27 are then bent upon the scored lines so as to assume the position shown in Figs. 8 and 11, thus providing relatively thick flanged ends 29 and 30. The portions 31 between the notches 28 are then bent downwardly to form flaps 32 and spaces or openings 32a, as clearly shown in Figs. 8 and 9 and pads 33, bent to the form clearly shown in Fig. 8, are mounted upon the top plate and partly project into the openings 32a, as shown. With these pads 33, in connection with the top plate, the upper part of the cabinet 4 is spaced from the side and end walls of the carton 1, as clearly shown in Figs. 7 and 11. The radio cabinet is mounted between side flaps 32 which are reinforced by side pads 33 and between flanged ends 29 and 30, so that there can be no movement either longitudinally or laterally of the cabinet relative to the top plate 27, thereby preventing the cabinet from frictional or rubbing engagement therewith and thus preventing marring of the surface of the cabinet. The width of the side pads 33 are such that when the end flaps 3 of the carton 1 are folded inwardly the flat portion 33a of said pads is locked against movement within the carton, as clearly shown in Fig. 7.

I have found that by forming the inner supports as above described they are not only stronger than supports heretofore used for the purposes specified but, due to their peculiar construction, remain in their intended position within the carton before or after inserting the article to be shipped. They are constructed in such a way that they will stand in a vertical position parallel with the wall of the carton and there is nothing in their construction that will cause them to expand and force themselves out of parallel alignment with the wall of the carton.

In a previous application filed by me in the Patent Office I show an inner support for fibreboard cartons but due to the construction there shown the support does not maintain its proper placement within the carton unless held in place until the article to be shipped is inserted within the carton, which results in considerable loss of time in packing and which requires to be assembled and reas-

sembled by the shipper, as its construction will not hold it together, as is the case with the present inner support. The support of the present invention is self-contained, that is, it can be assembled by the box manufacturer and shipped to the packer ready for installation within a carton. Further, due to its construction, after being placed within a carton, it will retain its proper placement in a highly satisfactory manner.

5 An advantage of my invention is that the interlocking and supporting members have no tongues or extensions that will interfere with their easy insertion within the carton. Without a tongue or extension at the point 15 where the fibre support comes into contact with the wooden brace an easy means is afforded to catch hold of the support to remove the complete interlocking unit from the carton.

20 Radio cabinets and other articles frequently have portions which project beyond the main body of the article, such as knobs or enlarged portions on legs or the main body 25 may have outwardly projecting portions. One of the advantages of my invention is that the top or cover plate can be readily varied in length by making greater or less 30 number of folds, as may be necessary in the flanged ends 29 and can be varied in width by making a greater or less number of folds in the pads 33.

35 Some of the advantages of my invention over prior constructions are that the supporting unit, formed of interlocking members, maintains all pieces in upright or vertical position at all times and allows all supporting members to stand flat against the end of the shipping carton without forcing it away in any manner from either end thereof; also 40 the arrangement of the slots affords a ready and convenient means of interlocking the upright supporting members with the retaining or spacing members in such a way that these parts can be readily and conveniently 45 assembled together by the manufacturer, ready for insertion in the carton by the user and also eliminates the necessity and inconvenience of assembling these parts in the 50 carton. The parts can be cut and scored and stacked flat ready for storage or shipment and can be easily and speedily assembled into units before being put into the containers. Furthermore, it is adapted to hold the cabinet in fixed position within the container and permits the detachable mounting of the 55 cabinet thereon so that when the container is opened, the cabinet can be removed without the withdrawal of any nails or other 60 fastening means.

65 While I have shown and described one particular embodiment of my invention, it will be understood that various changes and modifications can be made without departing from the scope or spirit thereof as, for ex-

ample, for light packing the wedge strengthening support 21 can be entirely dispensed with. In practice I have used single wall corrugated fibreboard to make the body 5 of the inner support and double-wall corrugated fibreboard for use in making the flat panels 19 and a relatively stiff solid piece of fibreboard for the wedge strips 21, it being understood, of course, that other thicknesses or weights of fibreboard can be used, depending entirely upon the weight of the article to be shipped within the carton 1.

Having thus described my invention, what I claim as new and desire to secure by Letters Patent is:

1. In a shipping carton, a pair of units each comprising an upright flanged and slotted retaining, spacing and supporting member detachably interlocked with a flat slotted panel, said units being adapted for 85 detachable mounting in the respective ends of a carton, for the purposes specified.

2. In a shipping carton, a pair of units each comprising an upright flanged retaining, spacing and supporting member detachably connected with a supporting panel, said units being adapted to be removably mounted within the respective ends of a carton, for the purposes specified.

3. A shipping carton comprising a container having detachably mounted therein an upright flanged and slotted retaining, spacing and supporting member having its central portion inset, in combination with a slotted interlocking panel.

4. A shipping carton comprising an outer fibreboard body with means to close the top and bottom thereof, a pair of inner supporting members, each of which comprises a main blank scored in a plurality of places 105 and provided with spaced apart slots to form an inset, a plurality of flat panels adapted to interlock with said inset and a wedge strengthening strip inserted between said panels and inset, substantially as described and for the purposes specified.

5. A shipping carton comprising an outer fibreboard body with means to close the top and bottom thereof, a pair of inner supporting members each comprising a blank of 115 fibreboard creased to provide end walls with integrally formed relatively short side walls, an inset central portion integrally formed with said end walls and a plurality of flat panels adapted to interlock with said inset 120 portion.

6. In combination with a shipping carton, inner supporting members therefor comprising a main body member scored and died out to supply, when bent, side walls, end walls and a U-shaped inset member integrally formed with said side walls, a depending support integrally attached to said U-shaped inset member, the side walls of 130 said U-shaped member being disposed in a

plane parallel to said side walls of said body member and a plurality of slotted panels, the slots of which are adapted to receive the side walls of said U-shaped inset member to thereby frictionally hold said panels and body in detachably interlocked relation relative to one another.

7. In combination with a shipping carton, a top insert plate therefor comprising a blank scored at opposite ends and slotted between the scored lines to provide inwardly projecting tabs, side pads adapted to be received adjacent said tabs, and end pads formed at opposite ends of said plate by bending the plate upon itself at the scored lines, substantially as set forth and for the purposes specified.

8. A shipping carton comprising a container having detachably mounted within each end thereof an upright flanged and slotted retaining, spacing and supporting member having its central portion inset, in combination with a plurality of slotted double-walled corrugated fibreboard detachably interlocking panels with solid fibreboard strengthening wedges interposed between said panels, substantially as set forth and for the purposes specified.
